UNITED STATES PATENT OFFICE

FRITZ ISRAELSON, OF STOCKHOLM, SWEDEN

STRAIGHT-FRAME KNITTING MACHINE

Application filed November 14, 1927, Serial No. 233,117, and in Sweden January 25, 1927.

This invention relates to straight frame knitting machines of the Lamb type and more particularly to means for enabling the production of longitudinally striped or patterned knitted wares in such machines. Proposals have already been made to enable such knitting operations in machines of said type but have resulted in complicated auxiliary mechanisms. The invention has for its object to secure the same result by exceedingly simple and easily controlled means.

The invention is characterized, chiefly, in that in front of the cam lock or each cam lock of the carriage serving to guide the needle butts during the stitch forming operation there is provided a needle guiding channel having a point lever pivoted in it and controlled by a spring tending to maintain said point lever in its one extreme position in which it allows the needles to enter a section of said channel leading to the cam slot formed by the respective cam lock, while the lever, after having been moved to its opposite extreme position, will cause the needles to pass outside said cam slot, that section of said guiding channel through which the needle butts pass in said last mentioned case being of such a shape that a needle butt, passing through said section of the channel, will automatically swing the point lever on its pivot so as to allow a further needle butt to enter said channel section.

In the drawings one embodiment of the invention is illustrated. Fig. 1 is a view of the under side of the foremost half portion of the carriage of a straight frame knitting machine. Figs. 2^a-2^c illustrate in a diagrammatic manner a striped knitting produced by a knitting machine according to the invention. Fig. 3 is a plan view of a mechanism to control the pattern knitting device according to this invention. Fig. 4 is an end view of said controlling mechanism.

A straight frame knitting machine of the Lamb type comprises, as is well-known, two rows of needles mounted in a frame in the form of an inverted V and operated by a reciprocating carriage. Said carriage is indicated by the reference numeral 1 in Fig. 1 and carries in the usual way a cam lock to

guide the needle butts during the stitch forming operation, said cam lock comprising the lowering cams 2, 3 and the lifting cams 4, 5, 6. The lifting cam 5 is formed integral with a lever pivoted at 7 to the carriage, said pivot also carrying a point lever 8. Said point lever 8 is situated in a needle guiding channel formed between a non-adjustable or adjustable block 10 and another block 11. The block 10 is formed with a shoulder to be engaged by the point 9 of the lever 8, and when said point engages said shoulder, as shown in Fig. 1, a channel 12 will be formed for the needle butts between the upper edge of the lever 8 and the block 11. Those needle butts, which in the movement of the carriage to the right, that is, in the direction of the arrow a (Fig. 1), enter the channel 12 will be passed to the cam lock to be given therein the movement necessary for the stitch forming operation. If the point lever 8 is swung from the shoulder of block 10 needle butts are allowed to enter the channel portion 13 between the lever 8 and the block 10. Needle butts which in the movement of the carriage pass the channel 13 cannot enter the cam lock. The lever 8, as shown, is provided with a projection 14 on its side facing the block 10. A needle butt passing through the channel portion 13 will engage said projection 14, thereby swinging the lever 8 to allow a needle butt to enter the space 13 between the point 9 of the lever 8 and the block 10.

If the distance between the point and the projection 14 corresponds, for instance, to 10 pitches of needle and if five needle butts are introduced below the point lever 8 in the extreme right hand position of the carriage, the succeeding five needle butts will pass above said lever, then at the movement of the carriage there will, evidently, pass alternately five needle butts through the cam lock of the carriage and five needle butts below said cam lock.

In the following a description will be given of the manner in which said mechanism is used for producing patterned and striped knitted works. In this description it may be assumed that the cam lock of the rear carriage is so adjusted that stitch forming will

take place in both directions of movement. The cam lock of the front carriage is adjusted so as to form complete stitches in one direction of movement only. In the other direction of movement the needles will be lifted to such a level that they may seize yarn. Said needles, however, will not be lowered sufficiently by the succeeding lowering cam 3. The yarn loop which in the upward movement of a needle is moved to embrace the stem of the needle, after having previously engaged the needle hook, will not be pushed off from the needle but will come below the depending latch of the needle hook.

15 When the needles of the front bed pass the cam lock said yarn loop in the downward movement of the needle will lift the depending latch causing the latter to close the needle hook with the yarn in engagement therewith.

20 At the following stroke both of said loops will be pushed down on the needle stem, the yarn seized by the needle hook being passed through two yarn loops to form thicker stitches. Upon the movement of the carriage to the left all the needles will be caused to enter the knitting cams by means not shown and forming no part of the invention. The needles will be raised by cams 4 and 6 to take yarns.

25 Fig. 2 (2^a-2^e) illustrates how to effect a striped knitting by means of the machine the front carriage of which is provided with one point lever 8. In the end position of the carriage there are alternately introduced two needles into the channels 12 and 13, respectively. Black yarn is represented in the drawing by a single curved line or a single dot, red yarn by a double curved line or a circle. Fig. 2^a may be assumed to show the

30 appearance of a number of needles after the completion of a number of operating strokes with black yarn. The needles of the rear bed as well as those of the front bed carry yarn in their hooks, and the needles of the

35 front bed carry yarn loops over their latches too. In Fig. 2^b the same needles are shown after the carriage has completed an operating stroke from the right to the left with red yarn. In said stroke the needles a, b and e, f have formed complete stitches, c, d and g, h have been lowered to some extent by the lowering cam to remove the black yarn loop surrounding the needle latch. According to Fig. 2^b

40 all of the needles of the rear bed carry red yarn in their hooks, while at the front bed the needles a, b and e, f carry red yarn and the needles c, d and g, h black yarn from the

45 appearance of a number of needles after the preceding operating stroke. In the next operating stroke, that is, from the left to the right, all needles will be lifted to seize red yarn. The needles of the rear bed are completely lowered, those of the front bed only

50 to some extent. According to Fig. 2^c both

the front bed needles and the rear bed needles carry red yarn in their hooks, the front bed needles having, furthermore, a loop over their latches formed on the needles a, b and e, f by red yarn and on the needles c, d and g, h by black yarn. In the next operating stroke—that is, from the right to the left—the needles are operated so that a, b and e, f will pass below and c, d and g, h above the point lever 8. In this movement the said last-mentioned needles will form stitches of black yarn, the guides for said yarn having been put into operation in said stroke. The red yarn engaged by the needle hooks will be pushed up on the stem of the needles but will always be above the black yarn that has held the needle latches closed. In the stitch forming operation said last mentioned yarn will come to lie in front of the red yarn so as to conceal it, thereby forming a black stitch. The red yarn loops surrounding the needle latches a, b and e, f are pushed off over the red thread in the respective needle hooks whereby red stitches will be formed. According to Fig. 2^d, all of the needles carry yarn in their hooks. The needles of the rear bed as well as the needles c, d and g, h of the front bed carry black yarn, while the needles, a, b and e, f have retained in their hooks the red yarn seized in the preceding operating stroke. After a further operating stroke has been completed all of the needles, as shown in Fig. 2^e, will carry black yarn in their hooks and, in addition, the needles a, b and e, f will carry red loops and the needles c, d and g, h black loops upon their latches. Figs. 2^d and 2^e which are identical with 2^b and 2^c show the continuation of the stitch forming operation. From these figures it will be seen that the front bed needles a, b and e, f will form red stitches and the needles c, d and g, h black stitches, as according to the above description a black yarn of the said first mentioned needles will always be covered by a red yarn, and vice versa.

In order to facilitate the production of striped and patterned knitted works it is desired to use auxiliary means whereby during each operating stroke the desired number of needles may one time be distributed above and below the point lever. Figs. 3 and 4 show a preferred form of such means.

A spring operated lever 15 journaled to the carriage 1 embraces by its forked end a lateral projection 8^a of the lever 8 normally to maintain the free end 9 of the lever 8 in engagement with the block 10. Bearing against the lower side of lever 15 is a lever 15^b journaled on the carriage 1 at 15^c. Pivotally connected to lever 15^b at 15^d is a lever 15^e substantially of the shape of an inverted T. Lever 15^a is journaled on the carriage at 15^h and pivotally connected to the lever 15^a at 15^k is a lever 15ⁱ acted upon by a spring 15^j connected to one arm of the lever 15^a. A stop pin 15^m on

the lever 15^a limits the movement of lever 15ⁱ relative to lever 15^a under the action of the spring 15^e which spring however cannot overcome the action of spring 15^f of the lever 15.

5 Near one end of the machine frame a series of preferably spring operated, swingable arms 16 are journaled on a shaft 16^a parallel to the direction of movement of the carriage 1. Said arms 16 are obliquely cut at their free ends and so positioned that said free ends in the normal position of the arms 16 may cooperate with the correspondingly obliquely cut end of the lever 15ⁱ during the movement of the carriage. When the carriage is moved 10 to the left the lever 15ⁱ engages the straight sides of the arms 16 and is caused due to this engagement to turn on its pivot 15^k without lifting the lever 15^a. The needle distributing lever 8 will thus not be operated, allowing 15 all of the needles to pass thereabove. When, however, the carriage is moved to the right the lever 15ⁱ will engage the obliquely cut ends of the arms 16. Due to its engagement with the pin 15^m the lever 15ⁱ cannot 20 turn but will be lifted by said oblique ends, thereby, in turn lifting the lever 15^a which will now lift the lever 8 by means of the connection described. By proper adjustment of the arms 16 any desired distribution of the needles to the channels 12 and 13 may be obtained. It is to be noted, that the machine should have one selecting arm 16 for each 25 separate one of the needles that may be contained between the point 9 and the projection 30 14 of the lever 8.

In order to facilitate the knitting operation the machine may be fitted with means to automatically control the adjustment of the various selecting arms 16. To this end the 40 machine may be provided, as shown in Figs. 3 and 4, with a rotatable drum 17 having recesses 18 formed in it to be engaged by projections 19 of the arms 16. Any arm 16, the projection 19 of which is in engagement with 45 a recess 18, will assume such a position as to operate the lever arm 15^a to lift the point lever 8. Those arms 16 not engaging any recesses 18 cannot operate the lever arm 15^a and will thus cause the needles to pass above 50 the point lever 8 outside of the cam lock. It will be seen, that it is possible in this way to obtain the needle distribution desired. If the drum 17 is provided with a number of rows of recesses with different position of the 55 recesses in the several rows the needles may be automatically set for producing the pattern desired by rotation of the drum.

What I claim is:

1. In a straight frame knitting machine 60 the combination with the beds and their needles, of carriages reciprocating on said beds, cams on said carriages to form a knitting position for the needles, a set of other cams on said carriages in front of said knitting position, a shiftable lever between the

70 cams of said set to form two alternate passages to guide the needles into the knitting cams or outside thereof, means to normally cause said lever to keep one passage closed, and means to cause each needle introduced in said normally closed passage to automatically shift the lever to cause it to momentarily open said normally closed passage.

2. In a straight frame knitting machine 75 the combination with the beds and their needles, of carriages reciprocating on said beds, cams on said carriages to form a knitting position for the needles, a set of other cams on said carriages in front of said knitting position, a shiftable lever between the cams of said set and the knitting cams to form two alternate passages to guide the needles into the knitting cams or outside thereof, means to normally cause said lever to keep one passage closed by resting with its point 80 against the respective cam, and an abutment on the side of the lever facing said cam to be acted on by each needle passage along said side of the cam in order momentarily to shift the lever, said abutment being situated at 85 such a distance apart from said point that a certain number of needles may be contained therebetween at a time.

3. In a straight frame knitting machine 90 the combination with the beds and their needles, of carriages reciprocating on said beds, cams on said carriages to form a knitting position for the needles, other cams on said carriage in front of said knitting position, a shiftable lever between the cams to 95 form alternate needle guiding passages, a spring actuated lever system normally to cause the shiftable lever to keep one of said passages closed, and means to operate said lever system to open and close said passages in a predetermined order at the beginning of each operating stroke of the carriages, said last mentioned means comprising a set of selecting arms and a drum for actuating said arms whereby the latter are held in position 100 to engage the lever system or out of engagement with the latter.

In testimony whereof I have signed my name.
